CLAIM

The ornamental design for a combined desk lamp and controller, as shown and described.

DESCRIPTION

FIG. 1 is a front view of the combined desk lamp and controller, shown with the controller removed for clarity of the disclosure;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a front perspective view thereof;

FIG. 8 is a back perspective view thereof;

FIG. 9 is a front view of the combined desk lamp and controller shown with the desk lamp removed for clarity of the disclosure;

FIG. 10 is a back view thereof;

FIG. 11 is a left view thereof;

FIG. 12 is a right view thereof;

FIG. 13 is a top view thereof;

FIG. 14 is a bottom view thereof;

FIG. 15 is a front perspective view thereof;

FIG. 16 is a back perspective view thereof; and,

FIG. 17 is a partial enlarged view of an area labeled 17 in FIG. 1.

The dashed broken lines in the drawings depict portions of the combined desk lamp and controller that form no part of the claimed design. The additional broken lines surrounding the detail views in FIGS. 1 and 17 are for annotative purposes only and form no part thereof.

1 Claim, 17 Drawing Sheets
